METHOD FOR HYDRATING OLEFINES

Warren K. Lewis, Newton, Mass., assignor to
Standard Oil Development Company, a corpora-
tion of Delaware

Application October 22, 1936, Serial No. 106,967

13 Claims. (Cl. 260—641)

The present invention relates to an improved process for utilizing hydrocarbon gases and liquids for production of more valuable products, and particularly to an improved method for hydrating olefines for the production of alcohols, esters, and the like. The invention will be fully understood from the following description.

In the drawings Fig. 1 represents in semi-diagrammatic form a suitable apparatus for converting light petroleum liquids and gases into alcohols, and

Fig. 2 shows another arrangement of the reaction vessel and the recovery equipment.

The present specification is a continuation in part of prior applications, Serial No. 688,035, filed September 2, 1933, and Serial No. 737,361 filed July 28, 1934. These cases relate to improved methods for hydrating olefines so as to produce alcohols. In its broadest sense the process for hydrating olefines is known; for example, it is known to absorb olefines, either liquid or gaseous, in sulphuric acid of high strength or other similar absorbents, and then to dilute such absorbent to a large extent and to distill off the alcohol. In such case the acid is not strictly a catalyst because it emerges from the reaction in a more diluted form. In the present case as well as the applications referred to above, the process is strictly catalytic in that the absorption agent, for example sulphuric acid, is maintained throughout in a relatively diluted form, which is well below the concentration known to be suitable for sulphation at atmospheric pressures.

Referring to the drawings, Fig. 1 shows a pipe 1 through which oil or hydrocarbon gases are passed at high velocity. The gas or oil is cracked in the heated coil 2 which is arranged in a furnace setting 3. The exit products are cooled in the worm 4 and are conducted to a purifier 6 by line 5. The purifier may be in the form of a tower with inlet and outlet lines 7 and 8 for a suitable scrubbing liquid such as hydrocarbon oil. If desired, the scrubbing tower may be used to cool the cracked gases and suitable arrangements, such as a series of partial coolers or condensers, may be provided to segregate the normally liquid condensates such as gasoline, cracked gas oils, tar and the like, before the scrubbing steps. Such arrangements, being well known in the art, can be designed without difficulty. The gaseous fractions are removed by line 9.

The apparatus described in the foregoing paragraph is preferably operated at low or moderate pressures and the gases may be recompressed by the compressor 10 before passing into the subsequent steps. The compressed olefine gas passes into a reheater 11 and into a pipe 14 where it is admixed with superheated steam from pipe 13, which is also under the same high pressure. If olefine gas or light liquid olefines are available,

for example, from ordinary cracking still, it is not necessary to use the prior cracking coil 2 as such gas or liquid may be introduced under high pressure through the pipe 12. It may be desirable to crack only a sufficient quantity of gas to enrich the cracked gases available from the commercial cracking stills.

The olefines and steam are now admitted to the base of the reaction chamber 15. The tower is preferably provided with suitable means for maintaining it at a uniform temperature throughout, such as a jacket 16, but equivalent means such as electrically heated coils may be used. The tower is fitted with contact means such as tower packing or plates 17, fitted with bubbling caps and overflow pipes. The catalyst, which is a dilute aqueous solution, the exact composition of which will be disclosed below, is introduced at the upper chamber 18, flowing downwardly in contact with the upflowing stream of vaporized olefine and steam, and is drawn off at the base of the tower by a pipe 20 which carries the catalyst and such alcohol as is produced by the hydration of the olefines to the recovery equipment.

A reduction valve 21 is provided in the pipe 20 which reduces the pressure on the catalytic liquor before discharging into the recovery tower 22, which may be a simple distillation or stripping column provided with contact means 23, a closed heating coil 23a at the lower end and a pipe for the introduction of stripping gases. The alcohol is distilled over through a vapor pipe 25, to a condenser 26. The distillate is collected in receiving drum 27 and withdrawn to storage by pipe 28. A vent pipe 29 is provided on the receiver.

The catalytic liquor stripped of alcohol flows through pipe 30 to pump 31 and thence back to pipe 18 for reuse in the hydration tower.

In Fig. 2 a somewhat different arrangement of the reaction tower and recovery stream is shown. The same reference numerals are used throughout, where possible. The olefine and steam are introduced as before at pipes 11a and 13 respectively. The reaction tower 15 is fitted with alternate plates 11a and 11b and the overflow pipes are arranged so as to conduct the liquor on the various plates, not to the plate directly below but to the next lower plate. In this manner two separate streams of liquor flow downward through the tower, the gas and vapor rise through plates continuously and alternately contact with the two liquids, which, however, do not mix at any point. The catalytic liquor is introduced by the pipe 18 while the second liquid stream, preferably a non-catalytic liquor, is introduced through a pipe 18a.

Separate recovery and scrubbing towers 22 and 22a are provided for the two liquor streams 20 and 20a provided with reducing valves 21 and 60

21a and each is a substantial duplicate of the other and of the tower shown as 22 in Fig. 1. The stripped liquors flow down through the towers 22 and 22a and are separately recirculated to pipes 18 and 18a respectively so as to provide two complete but uncommunicating liquor circulation streams.

One object of the present process is to convert olefines, for example ethylene, the propylenes, 10 butylenes and higher homologues, either in a pure state or admixed with each other or with other gases, into corresponding alcohols. Cracked gases, preferably cracked at pressures below 100 lbs. per square inch, for example, and 15 even as low as atmospheric pressure, are preferred. The tops from stabilized cracked naphthas consisting of 60 to 70% propane, after removal of propylene with sulphuric acid, may serve as an excellent cracking stock, and when 20 cracked at 700 or 800° C. at low pressure, yields a considerably larger volume of a gaseous product containing 20 to 35% ethylene and 2 to 7% propylene. Such a material can be recompressed and fed directly to the reaction tower 15 for the 25 production of ethyl and isopropyl alcohols.

It will be understood that water must be furnished in order to hydrate the olefines and this may be furnished in different ways, for example, it may be included with the gases in the form of 30 steam and where the gases are very rich in olefines it is desirable to use this method since the steam assists as a heat carrier. Water may be added to the dilute acid catalyst at the top of the tower 16, if desired in the proper proportion. 35 The amount of water and steam to be added should be sufficient first, for the hydration reaction and second, to keep the off gases saturated so that the catalyst is not concentrated during the reaction by evaporation and loss of water. 40 The amount of steam will depend on temperature and pressure conditions although it is generally several times in excess of the amount of olefines present, say 2 or 3 or even 5 mols of steam added per mol of olefine.

45 The reaction temperature is below 350° C.; how much lower depending on factors such as catalyst, the time for conversion desired, degree of agitation of the reactants, and the rapidity of withdrawal of the alcohol from the tower. A 50 rapid reaction is obtained at 250° C., it is reasonably rapid at 120 to 150° C. and quite perceptible rates are found as low as 80° C. although, perhaps, too low for commercial application.

The temperature and pressure also depend on 55 the particular olefine or olefine mixture being reacted. In general the temperature should be decreased for higher olefines and this is especially true of reactive olefines containing a tertiary carbon atom combined with an adjacent 60 carbon atom having a double bond, such as in the case of isobutylene. Such olefines have a marked tendency to polymerize and the temperature for alcohol production should be quite low for example about 120° C. or lower and 65 under a suitable pressure for example for this particular temperature of about 150 atmospheres.

The pressure utilized in the present process depends on the particular temperature used, higher pressures being necessary as higher temperatures are used, but should in every case be sufficient to prevent any substantial evaporation of water and alcohols from the dilute catalytic liquor which is maintained at substantially the same concentration throughout the reaction tower. Obviously, at the temperature main- 75

tained and with the large volume of gas blown through it, there will be a tendency to evaporate, but the amount of steam used and the pressure imposed should be adjusted to substantially offset this tendency, and while variations in concentration of the catalytic liquor may be evident from time to time due to the difficulty in balancing all of these factors exactly, the object of the adjustment is to maintain as close a balance as possible to prevent evaporation of the catalyst and to maintain the alcohol formed in a liquid condition throughout the tower or at least to maintain the acid throughout at catalytic strength as will be defined below. For illustration it may be stated that the pressure is above 40 atmospheres and it is preferable to operate at 100 to 200 or even at 1000 atmospheres, it being understood that the yields decrease with pressure reduction. On the other hand, pressures above 400 atmospheres do not give proportional 20 advantages.

It has also been observed that there is a definite equilibrium alcohol concentration in the liquor within the tower and if this is reached the olefines pass through the tower without further conversion. This equilibrium concentration depends on the conditions of temperature and pressure to some extent, but principally on the olefine concentration of the gas. For example, if the olefine concentration in the gas is 10% ethylene, and the equilibrium concentration of ethyl alcohol is from 4 to 5%, when the ethylene concentration is about 20% at the same pressure and temperature the alcohol concentration for equilibrium is about 8 to 10%. It is highly desirable to always keep the alcohol concentration in the dilute acid liquor at a value well below the equilibrium concentration, and this may be accomplished in several different ways. For example, it has been found that if the acid catalyst is passed through the tower with sufficient rapidity, it is possible to decrease the alcoholic content to about one-half or less of the equilibrium concentration under the particular conditions of operation, and under these conditions the conversion is rapid and altogether the operation is highly successful.

Another means for controlling the alcohol concentration in the catalytic liquor is by use of the mechanical arrangements shown in Fig. 2. In this case two separate streams of liquor flow through the tower without intercommunication; the one is, of course, the dilute catalytic liquor and the other is a liquor capable of absorbing alcohol, but preferably non-catalytic in character. Of the latter type examples may be given. Hydrocarbon oils, for instance petroleum oils, may be used especially where the olefine is sufficiently high boiling to yield higher alcohols. Highly aromatic oils, phenols, especially alkyl phenols, which are liquid and readily dissolve the lower alcohols may also be used, but in producing lower alcohols such as ethyl and isopropyl alcohol an aqueous liquor is preferred. It is desired, of course, to provide a boiling point for the liquor such that it would not be distilled away at the temperature and pressure imposed, and for this purpose it has been found desirable to add very soluble salts to increase the boiling point, for example sodium or potassium sulphate or calcium chloride may be used for this purpose. It will be understood that a portion of the alcohol will be held in the catalytic liquor but it will be also understood that the alternate stream will also absorb a substan- 75

tial portion of the alcohol formed, and in this way assists in maintaining a concentration in the catalytic liquor well below the equilibrium value. It is also to be understood that there is 5 no substantial loss of alcohol by the vapor line 19. This gas may be used as fuel directly.

Another method of maintaining the alcohol concentration of the catalytic liquor below equilibrium values consists in adding to the catalytic 10 liquor a suitable organic acid such as a fatty acid which serves to esterify the alcohol on or after formation. If desired, a sufficient quantity of the fatty acid, for example acetic or higher acids, may be added to esterify substantially all of the 15 alcohol formed, or lesser quantities may be used so as to obtain alcohols and esters in any desired proportion. It is particularly desirable to use the apparatus illustrated in Fig. 2 in such a scheme, the fatty acid being admitted by pipe 20 18a for example. In this way it is possible to obtain alcohols and esters as separate cuts.

As to the time of contact, it will be understood that it is difficult to give clear-cut illustrations, but that the larger the tower and more contact 25 surface, the greater will be the proportion of olefine converted. Using a single 6" depth of dilute sulphuric acid, 40% of ethylene (pure ethylene) bubbled therethrough was converted to ethyl alcohol at a temperature of 250° C., 30 while at 140° C. about 11% of the ethylene was so converted. It will be understood that this factor is so closely related to temperature, catalyst and other conditions that it may vary greatly, depending on particular installation. In order 35 to obtain good yields it is essential to obtain a series of contact steps such as are obtained in a tower, especially when dilute olefine gases are treated.

The catalysts which may be employed are of 40 several types, most of which have been previously used at low pressure in high concentration and under such conditions are known to hydrate olefines. Such absorption is probably 45 chemical as distinguished from a mere physical solution. The catalysts used may be best described as "diluted absorption agents" and by such terms it is meant that the dilution is sufficient to prevent absorption at normal or moderate pressures or is below what is now known 50 in the art as a "sulphating strength" at low pressure. Among the mineral acids hydrochloric and other halide acids may be used but the less volatile and more stable mineral acids, such as sulphuric and phosphoric are preferred. Organic 55 acids such as acetic and oxalic are useful but metal halides, such as those of cadmium, zinc, ammonium and aluminum are better. In general it may be said that the higher the acid strength of the catalyst, the lower is its effective 60 concentration in the present process.

With different catalysts, different concentrations are preferable. For example, with phosphoric acid concentration rapidly increases the 65 yield for ethylene up to a maximum at about 15% but beyond that concentration the activity decreases markedly. The activity with 5% phosphoric acid is much greater at 300° C. and 400 atmospheres than with the stronger acids as used 70 in the prior art. Six percent sulphuric acid is satisfactory, although it may be used in lower concentrations, say from 1 to 4% or 10% or somewhat higher, but always well below 1.6 specific gravity which is the lower limit for absorption 75 at normal or moderate pressures. Again,

however, high pressures appear to favor the low acid concentrations which are useless at atmospheric and moderate pressure. Some of the catalysts effect considerable polymerization and of these sulphuric acid is one. Phosphoric acid on 5 the other hand, while apparently somewhat less active, does not effect polymerization of the olefine to anything like the same extent. Ten per cent acetic acid is not so good as 2% hydrochloric acid and boric acid has been found to be 10 even less active. With various metal salts the concentrations are likewise varied and a few tests are required to show the optimum concentration. With aluminum chloride ($AlCl_3 \cdot 6H_2O$) 15 to 20% solution gives an optimum output at 300° C. while 15 zinc chloride is apparently the best at about 50%.

In addition to the above, it should also be noted that silver salts can be used for catalytic purposes, and while perhaps not so satisfactory alone, they are decidedly advantageous when added to 20 other catalysts, for example, to sulphuric acid. Hydrocarbon oils may also be added to the catalytic liquor to assist in the absorption of the olefines, or Turkey red oil and similar materials may be used in its stead. 25

It is believed that the operation of the reaction vessel will be fully understood from the above description and little need be said as to the operation of the recovery steps. This recovery is merely a distillation of the alcohol or ester that 30 is formed from the catalytic liquor. The distillation is conducted at a pressure below that at which reaction is obtained, but it is not necessary to operate under vacuum or even at atmospheric pressure and it is usually, in fact, desirable 35 to distill under a positive pressure, such pressure being selected so that the distillation of the alcohol can be accomplished at approximately the same temperature as is maintained in the reaction tower. In this way waste heat is reduced 40 to a minimum and the operation is conducted under the most favorable conditions.

The apparatus must, of course, be designed to withstand the pressures and temperatures mentioned throughout and also to withstand the corrosive effects of the catalytic agents, particularly such as are of acid reaction. It has been found that with sulphuric acid a copper lining is satisfactory for the reaction and distillation vessels, although other linings, such as those of chromium 50 alloys may also be used.

As examples of the operation of the process the following may be considered.

Example 1

55

In the following first two experiments the gas used has the following compositions:

	Per cent
C_2H_4	39 60
C_3H_6	3.6
N_2	57.4

In the first test the gas was bubbled in a single stream of bubbles through a glass lined reaction 65 vessel containing 8% sulphuric acid in a single pool of 8 inch depth. The rate of gas flow was 2.5 to 3.5 volumes (at Standard conditions) per minute/volume of reaction space, which was under a total pressure of 3000 lbs. and at temperature of approximately 255° C. The gas was 70 continuously removed and it is found that 34% of the ethylene was converted to ethyl alcohol, i. e. approximately 15 pounds of ethyl alcohol per 1000 cu. ft. of gas. 75

Example 2

To contrast with the above procedure the acid was now allowed to flow through the reaction vessel in intimate counter-current contact with the rising gas. The rate of flow of gas was as before and that of the acid was about 900 pounds/1000 cu. ft. of inlet gas. The alcohol concentration of the exit acid liquor varied from about 5 to 6 gr./100 c. c. The conversion of ethylene proceeded smoothly to the extent of approximately 90%, giving a yield of about 45 pounds/1000 cu. ft. of gas and was removed from the acid liquor by distillation under reduced pressure. The exit gas contained from 3 to 4% ethylene and a trace of ethyl alcohol.

The effects of temperature and pressure on the operation of the process are shown by the following experiments:

20

Example 3

Gas containing 35% ethylene was bubbled once through a reaction vessel containing 10% sulphuric acid in a single pool of 6 inch depth. A temperature of approximately 140° C. and a pressure of approximately 3500 pounds per square inch was maintained. A four percent conversion of the ethylene entering was obtained.

30

Pure ethylene when reacted with 10% sulphuric acid maintained at a temperature of approximately 176° C. and under a pressure of approximately 197 atmospheres produces a solution containing 94 grams of ethyl alcohol per liter.

Example 4

Hydration of propylene to isopropyl alcohol.—At a temperature of approximately 138° C. and a pressure of approximately 184 atmospheres with a catalyst of 12.1% H₃PO₄, the following yields of isopropyl alcohol were obtained from propylene.

45

	Time of contact in hours	Grams isopropyl alcohol per liter produced
1.0		13.9
3.2		31
5.1		39
7.75		43

Example 5

The amounts of isopropyl alcohol produced by contacting propylene with 12.1% H₃PO₄ at a temperature of 161 to 164° C. varied as to the time of contact and pressure as follows:

60

	Time of contact in hours	Pressures			
		95 atmospheres	184 atmospheres	272 atmospheres	503 atmospheres
65	1.0	35	45	72	97
	2.0	61	70	110	137
	3.0	80	86	138	164
	4.0	92	98	152	176
	5.0	101	108	160	183
	10.0	120	134	181	204
	15.0	128	146	189	212

Example 6

A C₄ cut containing 17% isobutylene in the liquid phase when contacted with 3% hydro-

a pressure of 150 atmospheres produced 61 grams of tertiary butyl alcohol per liter in one hour.

Example 8

N-butlenes when contacted with 3% hydrochloric acid at a temperature of 147° C. and under a pressure of 150 atmospheres produced 45 grams of alcohol per liter in one hour.

The invention is not to be limited to any theory of the chemical reactions or of the functions of the several steps, nor to the use of any particular olefine or mixture of olefines or particular catalyst but only to the following claims in which it is desired to claim all novelty in the invention.

I claim:

1. An improved process for hydrating olefines comprising passing an olefine in vapor phase upwardly through a reaction zone in countercurrent contact with aqueous sulphuric acid of less than sulphating strength, the reaction being conducted at a temperature between about 350° and about 128° C. and at a pressure above about 100 atmospheres, maintaining a partial pressure of water to substantially maintain the concentration of the acid during reaction, maintaining the alcohol in liquid phase, dissolved in the aqueous sulphuric acid at a concentration below the equilibrium concentration, withdrawing a mixture of alcohol and dilute sulphuric acid and distilling the former from the latter at a pressure below that prevailing during reaction.

2. An improved process for the hydration of olefines which comprises continuously passing an olefine into contact with a dilute aqueous hydration catalyst providing intimate contact in a series of steps at a reaction temperature between about 350° C. and about 250° C. while under a reaction pressure above atmospheric and exceeding the vapor pressure of alcohol formed by the reaction, maintaining a partial pressure of water by addition thereof to prevent substantial concentration of the catalytic solution, whereby the olefine is hydrated forming alcohol, continuously withdrawing the dilute catalytic solution containing alcohol dissolved therein at a concentration below the equilibrium concentration and recovering the alcohol therefrom by distillation at a pressure below that prevailing during reaction.

3. Process according to claim 2 in which the olefine is passed upwardly in contact with the downwardly flowing stream of the dilute aqueous catalyst.

4. Process according to claim 2 in which the olefine in vapor form is passed upwardly in countercurrent contact with the downwardly flowing stream of the dilute aqueous catalyst, the pressure and temperature of the operation being interadjusted so as to obtain the alcohol in liquid phase, separating the alcohol from the acid liquor and recirculating the latter.

5. An improved process for hydrating olefines comprising passing an olefine in vapor phase upwardly through a reaction zone in countercurrent contact with aqueous sulphuric acid of less than sulphating strength, the reaction being conducted at a temperature between about 350° and about 250° C. and at a pressure above about 100 atmospheres, maintaining a partial pressure of water to substantially maintain the concentration of the acid during the reaction, maintaining the alcohol in liquid phase dissolved in the aqueous sulphuric acid at a concentration below the equilibrium concentration, withdrawing a mixture of alcohol and dilute sulphuric

acid and distilling the former from the latter at a pressure below that prevailing during the reaction.

6. Process according to claim 5 in which the acid strength is maintained constantly at from about 1 to 10%.

7. Process according to claim 5 in which the alcohol concentration in the acid catalytic liquor is maintained well below the equilibrium value.

10 8. Process according to claim 5 in which the alcohol concentration in the acid catalytic liquor is maintained well below the equilibrium value by maintaining a rapid flow of acid through the reaction zone.

15 9. Process according to claim 5 in which the alcohol concentration in the acid catalytic liquor is maintained well below the equilibrium value by introducing a non-catalytic liquor, maintaining it out of contact with the sulphuric acid, 20 withdrawing the same and recovering alcohol therefrom.

25 10. Process according to claim 5 in which the alcohol concentration in the acid catalytic liquor is maintained well below the equilibrium value by adding an esterifying organic acid to the reaction zone and thereby esterifying a portion of the alcohol formed.

30 11. Process according to claim 5 in which the alcohol concentration in the acid catalytic liquor is maintained well below the equilibrium value by adding a fatty acid to the reaction zone.

35 12. An improved process for the hydration of olefines which comprises continuously passing cracked gases produced by cracking petroleum hydrocarbons at elevated temperatures into contact with a dilute aqueous hydration catalyst

providing intimate contact in a series of steps at a reaction temperature between about 250° and about 350° C., while under a reaction pressure above atmospheric and exceeding the vapor pressure of alcohols formed by the reactions, maintaining a partial pressure of water by addition thereof to prevent substantial concentration of the catalytic solution, whereby the olefines are hydrated forming alcohols, continuously withdrawing cracked gases substantially free of alcohol forming olefines and their derivatives, continuously withdrawing the dilute catalytic solution containing alcohols dissolved therein at a concentration below the equilibrium concentration and recovering the alcohols therefrom by 10 distillation at a pressure below that prevailing during the reactions.

15 13. An improved process for the hydration of olefines which comprises continuously passing an olefine into contact with a dilute aqueous hydration catalyst providing intimate contact in a series of steps at a reaction temperature between about 350° C. and about 80° C. while under a reaction pressure above atmospheric and exceeding the vapor pressure of alcohol formed 20 by the reaction, maintaining a partial pressure of water by addition thereof to prevent substantial concentration of the catalytic solution, whereby the olefine is hydrated forming alcohol, continuously withdrawing the dilute catalytic solution containing alcohol dissolved therein at a concentration below the equilibrium concentration and recovering the alcohol therefrom by distillation at a pressure below that prevailing 25 during reaction.
